(57) **CLAIM**

The ornamental design of an injection device, as shown and described.

DESCRIPTION

FIG. 1 is a side view of the injection device showing our design;

FIG. 2 is a side view thereof rotated axially 90 degrees from FIG. 1;

FIG. 3 is a side view thereof rotated axially 180 degrees from FIG. 2;

FIG. 4 is a side view thereof rotated axially 180 degrees from FIG. 1;

FIG. 5 is a plan view of the distal end thereof;

FIG. 6 is a plan view proximal end thereof; and,

FIG. 7 is a perspective view of the proximal end and side thereof.

The broken lines illustrate structure or features which form no part of the claimed design.

The drawings include surface shading which represents contour and not surface ornamentation.
